UNITED STATES PATENT OFFICE.

EDWARD R. PIERSON, OF WESTFIELD, NEW JERSEY.

WAGON-JACK.

SPECIFICATION forming part of Letters Patent No. 240,610, dated April 26, 1881.

Application filed November 27, 1880. (No model.)

To all whom it may concern:

Be it known that I, EDWARD R. PIERSON, of Westfield, in the county of Union and State of New Jersey, have invented certain new and 5 useful Improvements in Wagon-Jacks, of which the following specification is a description.

This invention relates to an improvement in that class of lifting apparatus commonly called "wagon-jacks," for raising the bodies and 10 wheels of wagons, carriages, and other vehicles from the ground, so that certain parts thereof may be readily got at for the purpose of cleaning, greasing, or repairing the same, the object of my invention being to produce a wagon-jack in which the frame, lifting-bar, and lever 15 can be made entirely of wood, so as to save expense, the complete apparatus being light, compact, and easily handled, and at the same time capable of adjustment to wheels of different 20 heights.

The invention consists in the combination of a lifting-bar arranged to slide in an upright frame, and carrying an adjustable rest at its upper end, with a straight lever pivoted in said 25 frame, and having its upper end expanded on both sides to form a cam or eccentric, which bears against said lifting-bar and operates the same.

In the accompanying drawings, Figure 1 is 30 a perspective view of my wagon-jack. Fig. 2 is a front view of the same; and Fig. 3 is a vertical section thereof, taken on the plane of the line xx , Fig. 2.

Similar letters of reference indicate corresponding parts in all the figures.

In the drawings, A designates the bed of my wagon-jack, supporting an upright frame consisting of two strips, B B', the inner faces of which are grooved vertically their entire length 40 to receive the lifting-bar C. This lifting-bar C fits into the grooves in the strips B B' forming the frame, that portion of the bar arranged to slide in the grooves being left open nearly its entire length to permit the free operation

45 of a combined lever and cam or eccentric, hereinafter described. The upper portion of the bar C is not so wide as the lower portion, and one face thereof is provided with a series of transverse notches, nn , into which the ends of 50 a metal bail, b, can be sprung to adjust a rest, r, to wheels of different heights. This adjustable rest r consists of a block of wood with a

broad surface adapted to bear against the axle or other part of a vehicle. Its inner side is straight and fits snugly against the smooth 55 side of the bar C, and its outer side is beveled off and provided with a V-shaped transverse groove, into which I secure the bail b, the ends of which are adapted to fit in the notches nn of the bar C.

In the upper part of the lifting-bar C, I make a vertical slot, s, and set therein a screw, s' , or other guiding arrangement, the head of which slides in a groove, g, in the slot s. This screw s' is fastened to the rest r, and prevents lateral 65 displacement of the rest, as the screw-head is larger than the diameter of the slot s; but it does not interfere with the adjustment of the rest to different heights on the bar C.

I make the top of the lifting-bar C flat, so 70 that it may be employed independently of the rest r to raise any part of a vehicle, as in many cases it will be just the right height, and the rest r need not be brought into play. It will thus be seen that by this arrangement I provide two bearing surfaces on the lifting-bar C, either of which, when properly brought into contact with the object to be raised, can be operated to perform its function by the same lever, as will hereinafter be described.

I designates the lever consisting of a straight lever-arm expanded on both sides at its upper end to form a cam or eccentric, E. This lever L is hung vertically between the strips B B', being pivoted therein by a pivot-pin, p, which 85 passes from side to side of the frame through the cam or eccentric E, at a point nearly on a line with the center of the straight lever-arm. When the lever L is moved so as to bring the full side of the eccentric E against the lifting-bar, the lifting-bar can then be raised to its highest point by forcing the lever upwardly, and by passing the lever-arm through the frame and then raising it on the other side as far as it will go, the lifting-bar will gradually 90 descend until its lower ends rest on the bed A.

In practice the lower ends of the lifting-bar will be permitted to fall until they rest on the bed A. Then the lifting-bar will be brought under the axle of the vehicle, and the lever 100 forced down. If this operation does not clear the wheels of the ground, the lever can be passed through the frame and raised on the other side until the wheels are cleared. No

inconvenience will be caused by passing the lever through the frame in this operation, as the eccentric E does not operate to force the bar upwardly until the lever has passed through the frame, so that the operator can take hold of it on the other side. The lifting-bar is firmly held at any desired height by friction alone, thus obviating the necessity of using ratchets or other holding devices in connection with the lever.

It will be seen that there is very little strain on the lifting-bar and lever, as the strain is in a vertical direction, and hence will be received by the pivot-pin and upright frame.

What I claim as my invention, and desire to secure by Letters Patent, is—

1. The combination, in a wagon-jack, of the lifting-bar C, arranged to slide in vertical grooves in the uprights B B', and carrying an adjustable rest at its upper end, with the lever L, pivoted between said uprights, and having its upper end expanded to form the cam or eccentric E, substantially as set forth, for the purposes specified.

2. The combination, in a wagon-jack, of the lifting-bar C, having the vertical slot s, groove g, and transverse notches n n, with the adjustable rest r, bail b, and guiding-screw s', all constructed and arranged substantially as described, for the purposes specified.

3. The combination, in a wagon-jack, of the bed A, supporting the upright frame B B', lever L, cam or eccentric E, and pivot-pin p, with the lifting-bar C, having a vertical slot, s, groove g, and notches n n, and carrying an adjustable rest, r, attaching-bail b, and guiding-screw s', all constructed and arranged substantially as described, for the purposes specified.

The foregoing description of my invention signed by me this 25th day of October, A. D., 1880.

EDWARD R. PIERSON.
